CLAIM

The ornamental design for a vial assembly with actuator as shown and described.

DESCRIPTION

FIG. 1 is a top perspective view of a vial assembly with actuator showing the claimed design;

FIG. 2 is a bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The dotted broken lines in the drawings depict portions of the vial assembly with actuator that form no part of the claimed design. The dot-dash broken lines depict the boundaries of the claim and form no part thereof.

1 Claim, 5 Drawing Sheets
